United States Patent Office.

GIDEON SMOKER AND JONAS SMOKER, OF SMITHVILLE, OHIO.

Letters Patent No. 77,412, dated April 28, 1868.

COMBINED HAND-TRUCK AND SACK-HOLDER.

The Schedule referred to in these Letters Patent and making part of the same.

TO ALL WHOM IT MAY CONCERN:

Be it known that we, GIDEON SMOKER and JONAS SMOKER, of Smithville, in the county of Wayne, and State of Ohio, have invented certain new and useful Improvements in Hand-Trucks and Combined Sack-Holder; and we do hereby declare that the following is a full, clear, and exact description thereof, reference being had to the accompanying drawings, and to the letters of reference marked thereon, which form a part of this specification, in which—

Figure 1 represents a plan view of our invention,

Figure 2 a plan of the reverse side of the sliding-platform attachment, and

Figure 3 is a perspective view, showing the mouth of the sack open, when used in connection with our device.

The nature of this invention consists in the employment of a sliding platform, to which are attached springs, as and for the purpose hereinafter set forth.

To enable others skilled in the art to make and use our invention, we will now describe its construction and operation.

A represents an ordinary hand-truck, and B B its wheels.

C C represent two metal springs, secured at their inner ends to the sliding platform D, and curved or bent at their outer ends, the object of which will be more apparent hereafter.

D represents the sliding platform, made as seen in fig. 2, which slides back and forth in grooves cut in the sides of the truck. Said slide is designed to allow the springs to accommodate themselves to sacks of any size.

e e represent two hooks or pins, placed on the under side of the platform D, for the purpose of holding or securing one side of the mouth of the sack to the truck, the other side of the sack being held by the springs C C. Thus it will be seen that by this arrangement the mouth of the sack will be held open.

F F designate two sliding rods, which are furnished with spiral springs. Said rods are secured to the under side of the truck, one of their ends being fastened to the slide D, and their opposite ends playing back and forth in guides e e, on the lateral brace G. The object of this arrangement is to enable the platform D to be operated when necessary.

It will be observed that the guides e e, and the lower ends of the springs C C, furnish shoulders, whereby the springs on rods F F are held in position.

m m represent two curved metal bands, placed over the upper ends of the frame of the truck, to keep the slide D in place when not operated.

The operation of our invention is as follows: The truck is placed in a vertical position, and the mouth of the sack secured thereto, by tucking one side under the springs C C, and the other side under the pins or hook e e, and the bag is now ready to be filled.

It will be observed that by means of our device sacks of different sizes can be secured to the truck, for while the sack is being filled, its weight will cause the sliding platform to move downwards, and thus lower the springs to which the sack is attached, and allow the sack to rest in its proper place on the truck.

Having thus described our invention, what we claim as new, and desire to secure by Letters Patent, is—

The combination of the hand-truck A with sliding platform D, arranged to slide in grooves in the sides of the truck-frame, said platform being provided with springs C C and rods F F, upon which are spiral springs e e, all arranged as and for the purpose set forth.

In testimony that we claim the foregoing as our own, we have affixed our signatures in presence of two witnesses.

GIDEON SMOKER,
JONAS SMOKER.

Witnesses:

A. E. LEHMAN,
HENRY LEHMAN.
